FIG. 1

FIG. 1 is a front elevational view of a hanger embodying my new design; and

FIG. 2 is a cross-sectional view taken on line 2—2 of FIG. 1.

The fragmentary broken line showing of clothing in FIG. 1 is for purposes of illustration only.

This is a division of design application Ser. No. 14,711, filed Nov. 29, 1968.

I claim:

The ornamental design for a hanger, substantially as shown and described.
